UNITED STATES PATENT OFFICE.

JOHN ZELLY, OF EATON, OHIO.

INTERCHANGEABLE WATCH MOVEMENT AND PENDANT.

SPECIFICATION forming part of Letters Patent No. 695,852, dated March 18, 1902.

Application filed October 3, 1900. Serial No. 31,868. (No model.)

To all whom it may concern:

Be it known that I, JOHN ZELLY, a citizen of the United States, residing at Eaton, in the county of Preble and State of Ohio, have invented 5 a new and useful Interchangeable Watch Movement and Pendant, of which the following is a specification.

My present invention relates to a novel interchangeable watch movement and pendant; 10 but before proceeding with the detailed description of the construction and operation of the invention it may be well by way of premise to refer briefly to those considerations which have conduced to its conception 15 and development.

The art of watchmaking has of late years developed along a line tending to the production of watches comprising movements of high grade mounted within cases having the 20 appearance of solid gold, but produced at comparatively slight cost, for the purpose of bringing a first-class timepiece within the reach of persons unable to afford the elaborate and comparatively expensive cases of precious metal. 25 The class of cases to which reference is made are known as "gold-filled" cases, which are constructed from compound ingots or ingot-plates formed by uniting exceedingly-thin layers of precious metal upon 30 the opposite faces of a hard-metal base. The practical durability of filled cases has led to the universal guarantee thereof by the manufacturers for periods of from ten to twenty years. It has been found, however, that while 35 such guarantees greatly increase the demand for filled and heavily-plated cases considerable loss is sustained by the manufacturer by reason of the wearing away of the gold surfaces and the consequent necessity for making 40 good the guarantee upon the exposure of the base-metal filling. This objectionable result is due to several causes, chief among which are certain occupations which subject the watchcases carried by the artisans or laborers engaged therein to influences which 45 have an abnormal tendency to destroy the precious-metal facings of the case. For instance, professional men may ordinarily wear a filled case for a period greatly in excess of 50 that named in the guarantee, while the farmer, laborer, or mechanic have been known to report the exposure of the base metal after car-

rying a filled case a comparatively short time. The reason of this is that persons of the latter class are constantly engaged in rough 55 work, and the pockets in which the watches are carried contain more or less gritty matter, and the watch is further subjected to the deleterious influences of perspiration. In view of these considerations it is desirable 60 that such artisans be provided with means whereby they may at all times enjoy the benefits derived from the constant use of a high-class watch-movement without subjecting the watchcase to the destructive influences en- 65 countered in their daily avocation.

To this end my invention comprehends the production of a watch comprising a movement adapted for interchangeable mounting in a plurality of cases, one of which latter being constructed wholly or in part of precious metal and the other of any suitable inexpensive material designed for the reception of the movement when the wearer is engaged in employment conducive to the wear and 70 mutilation of the watch.

The invention also contemplates the provision of a plurality of interchangeable pendants to match the cases, such pendants being constructed in a novel manner and adapted 75 to effect the retention or release of the movement from the case without necessity for the employment of securing devices—as, for instance, screws, rivets, or the like—which would necessitate the services of a skilled 80 watchmaker for the purpose of effecting an interchange of cases and pendants. In other words, one of the primary objects of the invention is to produce a watch-movement provided with a movable pendant and winding- 85 arbor and with catches for retaining the movement in the watchcase and for retaining the front cap of the case, said catches being arranged for operation by the winding-arbor, while permitting the detachment of the pendant and arbor from the movement for the purpose of effecting the interchange of cases and pendants by the owner of the watch without skilled assistance, in order that the artisan may quickly and conveniently equip the 90 movement with a high or low grade case and pendant for the purpose of preventing the wear of a high-grade case when the watch is necessarily subjected to rough usage. In 95

these aspects the interests of both user and manufacturer are subserved, inasmuch as the preservation of the high-grade case is of equal interest to both.

- 5 The invention may be viewed, however, from still another standpoint—namely, that of an individual watchmaker, who is frequently seriously inconvenienced during the placing of the movement within the movement-ring by reason of the protrusion therein of the inner end of the winding-arbor, which in ordinary constructions cannot be withdrawn entirely from within the ring. This objection is fully overcome in my invention by reason of the removable mounting of the pendant and arbor, to the end that both may be entirely withdrawn from the movement-ring to facilitate the insertion or withdrawal of the movement proper.
- 10 There is still another important and perhaps primary object of the invention, and its accomplishment is rendered possible by reason of the movable mounting of the pendant upon the movement-ring. This object is the elimination of the objection commonly urged against stem-setting watches, wherein the stem or winding-arbor is pulled out slightly for the purpose of disconnecting its inner end from the winding mechanism and of operatively connecting said end with the setting device. This outward movement of the stem or arbor is effected by a pull upon the crown; but for reasons well known in the art undue force is frequently necessary to effect the proper withdrawal of the arbor to effect the setting of the watch, and the owner of the timepiece is frequently compelled to secure the services of a watchmaker whenever its regulation is desired. As stated, this objectionable feature of stem-setting watches is overcome in my construction by utilizing the movability of the pendant for the purpose of shifting the arbor longitudinally into engagement with the winding and setting mechanisms of the movement.
- 15 Various objects subordinate to those enumerated will hereinafter appear, and the means whereby the various ends sought are attained will appear in the succeeding description when taken in connection with the accompanying drawings, in which I have illustrated a preferred embodiment of my invention and several modifications thereof.
- 20 In said drawings, Figure 1 is a face view of a watch with the front cap open. Fig. 1^a is a detail perspective view showing a portion of the case and the pendant in juxtaposition to illustrate the manner in which the pendant is interlocked with the case. Fig. 2 is a sectional elevation of the subject-matter of Fig. 1 with the movement proper omitted. Fig. 3 is an enlarged sectional elevation of the novel subject-matter illustrated in Fig. 2. Fig. 4 is a sectional elevation on the line 4 4 of Fig. 2. Fig. 5 is a similar view on the line 5 5 of Fig. 2. Fig. 6 is a sectional view on the line 6 6 of Fig. 2, showing certain of

the parts in dotted lines and the movement-catch and pendant-catch in elevation. Fig. 7 is an enlarged elevation of the pendant detached. Fig. 8 is a sectional elevation of a modification of my invention comprehending a double movement-catch carried by the catch-spring which serves as a support for the case-catch. Fig. 9 is a detail perspective view of the case and movement catches detached. Fig. 10 is a sectional elevation of a portion of a watch, illustrating a still further modification of my invention, comprehending an inversion of the screw connection between the pendant and movement ring and the variation of the construction and arrangement of the catches. Fig. 11 is a detail view of the catch-spring and spring-casing shown in Fig. 10. Fig. 12 is a detail view of the pendant employed in the modified form illustrated in Fig. 10. Fig. 13 is a still further variation of the mounting of the catches. Fig. 14 is a detail perspective view of the case and movement catches detached. Fig. 15 is a fragmentary sectional elevation illustrating a still further modification of the detachable connection of the pendant to the movement-ring. Fig. 16 is a detail view of a portion of the pendant-ring shown in the preceding figure, and Fig. 17 is a detail view of the catch employed in this form of the invention.

Referring to the numerals of reference employed to designate corresponding parts throughout the views, 1 indicates that part of a watchcase known in the art as a case-center, which is that annular band within which the movement is located. The case-center 1 is closed at its rear side by the back cap 2, which may or may not be made integral therewith, as the special form of the watch-case is not essential to the application of my invention. At the front side of the case-center is formed, as usual, an inwardly-extending annular flange 3, and the front cap 4 is hinged in the manner of the ordinary hunting-case-watch construction to close the front of the case. At a point diametrically opposite the hinge connection the cap 4 is provided with an inwardly-extending lip 5, designed to be engaged by the case-catch to be hereinafter described. It is usual in the art to provide a case of the character described with a watch-movement mounted within what is known as a "movement-ring" or "annulus," the ring and movement being removable from the case. In carrying out my invention, however, I provide a movement-ring which is not only removable from the case, but which is additionally provided with a removable pendant designed to perform all of its ordinary functions, while being capable of complete detachment for the purpose of substituting another pendant, whereby, as premised, the movement may be employed in connection with various cases and pendants. By reference to the drawings it will be seen that the movement-ring 6 is provided with inwardly-extending annular

flanges 7 and 8, between which the movement proper is supported and upon which the dust-cap 9 and the bezel 10 are supported, the manner of connecting the dust-cap and bezel 5 to the movement-ring being non-essential, but the latter being arranged, as usual, to retain the crystal 11, which protects the dial and hands.

I have stated that the pendant is detachably secured to the movement-ring. Many expedients for effecting this connection may be employed, inasmuch as this structural peculiarity appears to be broadly novel; but an effective and perhaps preferable way of securing 10 the pendant to the movement-ring comprehends the provision of a radial boss 12, preferably made integral with the ring and extended beyond the periphery thereof. The radial boss 12 is of tubular form to provide an axial passage 13, and it is externally screw-threaded, as indicated at 14. At a point opposite the boss the movement-ring is provided with a stud 15, designed to extend under the flange 3 of the case-center for the purpose of 15 coöoperating with the pendant and movement catch, to be described, in holding the movement-ring securely within the case-center, said pendant, as well as the stud and catch, having interlocking engagement with the case in a manner which will be made apparent. The pendant, which is indicated by the numeral 16, is hollow and is provided with an externally-angular collar 17, preferably formed as an integral part thereof and internally threaded, as indicated at 18, for the purpose of permitting the pendant to be screwed upon the boss 12 of the movement-ring.

19 indicates the usual winding stem or arbor passed axially through the pendant and 40 having its upper or outer end provided with a crown 20 and its inner end reduced to form the squared end 21 and a shoulder 22 at the upper end of the latter. Respecting all ordinary functions the operation of the winding 45 stem or arbor is ordinary, and while I have not deemed it necessary to illustrate the movement proper or timepiece it will be evident to those skilled in the art that normally the inner squared end 21 will be in operative 50 relation with the winding mechanism and that slight longitudinal withdrawal of the stem will disengage it from the winding mechanism and effect its coöperative engagement with the setting mechanism in the manner of 55 the ordinary stem winding and setting watch.

It will now be obvious that as the movement-ring is designed to be encircled by the case-center some provision must be made for the accommodation of the pendant, which is designed 60 to be attached to the movement-ring before the latter is inserted in the case. I therefore provide the case-center 1 with an angular recess 23 (see Fig. 1) for the reception of the collar 17 of the pendant, so that 65 after the stud 15 has been passed under the flange 3 the pendant may be passed into the

recess 23 to permit the movement-ring to lie snugly within the case. The usual pendant-ring 24 is attached to the pendant 16, as shown.

70

In the present embodiment of my invention I have illustrated a hunting-case, in which variety of watchcases a fly-spring 25 is mounted within the case-center and operates to urge the front cap 4 to its open position upon its release by the case-catch. This case-catch is designated by the numeral 26 and is carried by a catch-spring 27, arranged within the movement-ring, between the flanges thereof, and fastened at one end in any suitable manner—as, for instance, by the screw or pin 28. The case-catch is laterally offset from the catch-spring and extends through the front flange of the movement-ring, so that its position will be similar to that occupied in ordinary constructions for engagement with the lip 5 of the front cap of the case. The free extremity of the catch-spring 27 is provided with an aperture 29, coincident with a similar aperture 30, formed in the overlapping end 80 of a movement-catch spring 31, fixed at its opposite end within the movement-ring and provided with a movement-catch 32, extended through the rim of the movement-ring and designed to engage a recess or slot 33 in 90 a block 34, confined within the case-center. The squared end 21 of the winding-stem or arbor is passed through the coincident apertures 29 and 30 in the catch-spring and movement-catch spring, whereby the inward movement of the arbor will effect the presentation of the shoulder 22 to the catch-springs for the purpose of flexing them sufficiently to disengage the case-catch from the front cap of the case and the movement-catch from 100 the case-center. It is obvious, however, that it would be undesirable to release the movement-catch each time the front cap is released for the purpose of exposing the dial. I therefore proportion the case and movement catches in a manner to give the movement-catch a greater range of movement than that of the case-catch before effecting the release of the engaged member. By this means 110 it is evident that a comparatively slight inward movement of the stem will cause the disengagement of the case-catch from the front cap; but such movement will not be sufficient to withdraw the movement-catch 115 from engagement with the case-center. If 120 the release of the cap only is desired, no further movement of the stem is necessary; but if it is desired to remove the movement entirely from the case the stem is given a further movement, which effects the disengagement 125 of the movement-catch from the block 34 to permit the entire withdrawal of the movement-ring and movement from the case. In other words, the case and movement catches are mounted for successive release 130 by the inward movement of the winding-stem, the first period of movement effecting

the release of the case-catch and a subsequent period of movement effecting the release of the movement-catch.

It will be evident from the foregoing that 5 if it is desired to substitute another case and pendant for that employed in connection with the movement it is simply necessary to manipulate the winding-stem in the manner just explained to release the movement. The 10 movement-ring, with its attached pendant, is then lifted from the case and the pendant is unscrewed from the boss 12 and, with its winding-stem, is entirely removed from the movement-ring. An interchangeable pendant 15 matching the substitute case is then screwed upon the boss, and the movement-ring, equipped with the interchangeable substitute pendant, is placed in the substitute watch-case and is securely retained by the engagement of the stud 15 and the movement-catch 20 32 with the case-center.

In one aspect the construction thus far described constitutes a complete embodiment of my invention, since it comprehends a watch-movement interchangeably related to a plurality of watch cases and pendants, by reason of the fact that provision is made for its complete detachment from said cases and pendants and for its attachment to other cases 25 and pendants without necessity for the employment of skilled assistance and without recourse to separate attaching devices—as, for instance, screws, rivets, &c. I prefer, however, to carry my invention still further by 30 utilizing the relative movement of the pendant with respect to the movement-ring to effect such longitudinal movement of the winding-stem as is necessary to connect the latter with the winding or setting mechanism of the 35 watch. Ordinarily the stem is shifted in the ordinary manner by pulling or pushing upon the crown, as usual; but if, as is frequently the case, the stem should stick or work hard the movement-ring may be removed from the 40 case and the pendant manipulated to shift the stem. This result is attained by simply turning the pendant to the right or left, as the case may be, for the purpose of causing it to approach or recede from the movement-ring 45 50 under the control of the threaded connection between the pendant and boss. This movement of the pendant will move the winding-stem longitudinally when it is desired to wind or set the watch and obviates the necessity 55 for pulling upon the crown in the ordinary manner, although it is evident that the stem may be shifted by means of either the crown or pendant, as desired. The turning of the pendant while the movement is in the case 60 is prevented by reason of the engagement of the square, polygonal, or otherwise angularly-formed collar 17 with the recess in the pendant-ring, and the front cap of the case also assists in the secure retention of the parts. In like 65 manner a snap or screw bezel will greatly aid in the retention of the pendant when an open-face case is employed. As an additional

means for opposing resistance to the initial turning of the pendant after the latter has been screwed up, I provide what may be 70 termed a "pendant-catch" 35, yieldingly urged into engagement with a notch 36 in the inner end of the pendant, as clearly shown in Fig. 7. The pendant-catch may be entirely independent of the case and movement 75 catches; but I prefer to form it integral with the movement-catch 32 in order that the movement-catch spring 31 may be made to serve as a spring or yielding support for both the movement and pendant catches. The 80 pendant-catch has still another important function besides presenting a yielding resistance to the unscrewing of the pendant, which additional function is the prevention of the overscrewing of the pendant when it 85 is screwed to place. The notch 36, co-operating with the pendant-catch, is therefore formed with an inclined wall or face 37 and an abrupt face or wall 38, disposed in the longitudinal plane of the pendant. When the 90 pendant is screwed to place, the pendant-catch will be engaged by the straight face 38 to prevent overscrewing of the pendant and at the same time the initial movement of the pendant in a direction to unscrew it will be 95 resisted by the engagement of the pendant-catch of the inclined face 37. The form of the notch 36 is preferable, perhaps, as shown in the drawings; but I wish to reserve the right to vary it in accordance with contingencies of manufacture which may arise in the future. For instance, it may be expedient to give said notch some angular formation other than that shown, or the face 37 may be curved or the notch may be formed 100 by a curved depression without materially affecting the functions for which it is designed.

It will appear that we now have a watch-movement arranged to be used interchangeably in a number of watchcases and provided 110 with case and movement catches operated by the longitudinal movement of the winding-stem and provided with a detachable pendant capable of relative movement while connected with the movement-ring for the purpose 115 of operating the winding-stem to effect the engagement of the latter with the winding or setting mechanism of the watch, and it will further appear that said pendant when connected to a movement and inserted in a watch-case will have interlocking engagement with the latter, preventing accidental movement of the pendant while the watch is closed and likewise preventing the accidental withdrawal of the movement from the case-center. 125

In Figs. 8 and 9 I have illustrated a modification of the means for mounting the case and movement catches, such modifications comprising the employment of a single catch-spring carrying the case-catch 26 and supporting a catch-plate 39, having an opening 40, registering with the opening 29 in the catch-spring and provided with a plurality of movement-catches 41 and 42, the catch 41 be-

ing provided with an extension constituting the pendant-catch.

In Figs. 10 and 11 I have illustrated still a further modification, which comprehends the reversal of the screw connection between the pendant and movement-ring and a still further variation of the means for mounting the catches. In this construction the movement-ring is provided with an internally-threaded socket 43 for the reception of the reduced threaded end 44 of the pendant, the collar 17 of the latter being provided with a slot 45, extending through one side thereof, for the reception of a movement and stem catch 46, formed at one extremity of a spring 47, slidably mounted within a spring-casing 48, secured in any suitable manner within the case-center. The catch 46 passes through the slot 45 and enters an annular recess 49 in the winding-stem, so that while the spring 47 may be flexed through the movement of the winding-stem to withdraw the case-catch 50 from engagement with the front cap the winding-stem cannot be entirely withdrawn from the pendant or the pendant removed from the movement-ring or the movement-ring from the case until the spring 47 has been slid longitudinally to withdraw the catch 46 from engagement with the pendant.

In Figs. 13 and 14 I have shown a still further modification along the line just indicated, the variation of this structure over that shown in the group of figures just described being the elimination of the spring-casing 48 and the substitution of a fixed mounting for the spring 51, the free end of said spring being provided with a slidable plate 52, carrying the catch 53 and provided with a laterally-extending projection 54, protruding through an elongated slot 55 in a case-catch 56, formed integral with the spring 51. The function and operation of this structure are the same as that just described, except that instead of its being necessary to slide the spring bodily within the casing 48 it is simply necessary to move the plate 52 rearwardly until the catch carried thereby is withdrawn from the pendant.

In Figs. 15, 16, and 17 I have illustrated a still further modification of the invention, which relates merely to the detachable connection of the pendant with the movement-ring. In this embodiment the movement-ring 6 is provided with a peripheral depression or recess 57, from which extends a cylindrical post 58, provided with a laterally-extending pin 59. The collar of the pendant 16 is internally threaded for the reception of a divided cap 60, provided with a channel 61 to accommodate the pin 59, while the pendant is being slipped upon the post 58, after which the pendant is turned to cause the pin 59 to engage with the upper edge 62 of the cap 60 in order to prevent the withdrawal of the pendant from the movement-ring until the pin 59 has again been alined with the channel 61.

From the foregoing it will appear that I have originated a watch embodying a novel structure calculated to effect the accomplishment of the numerous desirable ends herein recited; but while the present embodiment of the invention appears at this time to be preferable I desire it to be distinctly understood that I do not limit myself to the various structural details defined, as, on the contrary, I reserve the right to effect such changes, modifications, and variations of the construction and arrangement of the various individual features of the device as may be embraced within the scope of the protection prayed.

What I claim is—

1. The combination with a watchcase of a movement-ring removably retained therein, and a separate pendant having detachable connection with the ring and interlocking engagement with the case to prevent its detachment from the ring while the movement is in the case.

2. The combination with a watchcase, of a movement-ring removably retained therein, a pendant having detachable connection with the ring and interlocking engagement with the case to prevent the detachment of the pendant while the ring is in the case, and means co-operating with the pendant to normally retain the ring within the case.

3. The combination with a watchcase and a movement-ring removably retained therein, of a pendant having detachable connection with the ring and interlocking engagement with the case, a winding-stem carried by the pendant, and a movement-catch serving to retain the movement-ring and located to be operated to release said ring by the movement of the stem relative to the pendant.

4. The combination with a movement-ring, of a relatively movable pendant carried thereby, a pendant-latch disposed to resist the movement of the pendant relative to the movement-ring, and a winding-stem disposed to actuate the pendant-latch, so that the pendant can be removed from the movement-ring.

5. The combination with a watchcase and a removable movement-ring, of a case-catch retaining a portion of the case, a movement-catch retaining the movement-ring within the case, and an actuating member common to said catches and disposed to operate them by different periods of movement in the same direction to effect the release of the case and movement, respectively.

6. The combination with a case and a movement-ring therein, of a catch-spring, a case-catch and a movement-catch operatively related to said spring, said movement-catch having a locking element extended from the periphery of the movement-ring into engagement with the case, and a stem in operative relation to said catches to effect their successive release through continued movement of the stem in the same direction.

7. The combination of a watchcase, a move-

- ment-ring fitted therein and removable therefrom, a catch for a cap of the case, a catch to secure said movement-ring in the case, said catches having outwardly-extending engaging elements of unequal length, and a winding-stem to operate the said catches and disengage the same successively by different degrees of inward movement, substantially as described.
10. 8. The combination with a watchcase, of a removable movement-ring therein, provided with a relatively movable pendant, a movement-catch retaining the movement-ring within the case, a pendant-catch controlling the movement of the pendant with respect to the ring, and actuating means common to said catches.
9. The combination with a watchcase, removable movement-ring and a pendant movable upon the ring, of a shiftable stem within the pendant, a movement-catch retaining the movement-ring in the case, and a pendant-catch engaging the pendant to retain it against movement relative to the ring, said catches being in operative relation to the stem for actuation thereby.
10. The combination with a watchcase, a removable movement-ring therein and a movable pendant carried by the movement-ring, of a movement-catch retaining the movement-ring within the case, a case-catch retaining a portion of the case, and a pendant-catch engaging the pendant.
11. The combination with a watchcase, a removable movement-ring therein and a movable pendant carried by the ring, of a movement-catch retaining the movement-ring within the case, a case-catch retaining a portion of the case, a pendant - catch engaging the pendant, and operating means common to the several catches to effect their release and the consequent disassociation of the case, movement-ring and pendant.
12. The combination with a watchcase, a removable movement-ring therein and a movable pendant carried by the ring, of a movement-catch retaining the movement-ring within the case, a case-catch retaining a portion of the case, a pendant-catch engaging the pendant, and a stem carried by the pendant and arranged to operate the several catches by different degrees of endwise movement.
13. The combination with a watchcase, and a removable movement-ring, of a pendant detachably connected to the ring said ring and pendant being locked together by the case.
14. The combination with a watchcase comprising the case proper and a movable cap, of a removable movement-ring mounted in the case, and a pendant detachably carried by the movement-ring, the watchcase proper and the case-cap being disposed to coöperate to lock the movement-ring and pendant together, and to prevent the withdrawal of the movement-ring from the case.
15. The combination with a watchcase and a removable movement-ring, of a pendant detachably carried by said ring and adjustable thereon, and a winding-stem removable from the movement-ring with the pendant and arranged to be shifted to its winding and setting positions through the adjustment of the pendant relative to the movement-ring, and a pendant-catch retaining the pendant and disposed for release by the stem.
16. The combination with a movement-ring, and a relatively movable pendant carried thereby, of a winding and setting stem shiftable carried by the pendant, and a pendant-catch engaging the pendant and disposed for operation by the movement of the stem relative to the pendant.
17. The combination with a movement-ring, and a relatively movable pendant carried thereby, of a winding and setting stem shiftable carried by the pendant, a pendant-catch carried by the ring and engaging the pendant, and means for operating the pendant-catch by the endwise movement of the stem.
18. In combination with a watchcase and a removable movement-ring carrying the movement, the removable and interchangeable pendant attached to the movement-ring and removable in connected relation therewith from the case and separable from the movement-ring only when the latter is out of the case, whereby the movement- ring and its movement may be interchangeably used with different pendants and cases.
19. The combination with a watchcase and a removable movement-ring, of a pendant removably mounted upon the movement-ring but removable therefrom only after the movement-ring is withdrawn from the case.
20. The combination with a watchcase and a removable movement-ring, of a pendant removably mounted upon the ring and held by the case against detachment from the ring, whereby said pendant can be removed from the movement-ring only when the latter has been withdrawn from the case.
21. The combination with a watchcase and a removable movement-ring, of a pendant removably mounted upon the movement-ring and locked by the case against movement, said pendant being removable from the movement-ring when the movement is withdrawn from the case, whereby the pendant serves as a handle to facilitate the withdrawal of the movement from the case.
22. The combination with a watchcase and a removable movement-ring, of a pendant removably mounted upon the movement-ring, and means for locking the pendant to the movement-ring while the latter is in the case and for releasing the pendant to permit its removal from the movement-ring after said movement-ring has been withdrawn from the case.
23. In a watch, the combination with a movement-ring and a shiftable winding and setting stem, of a pendant movable with respect to

the movement-ring to effect the shifting of said stem, and means for normally locking the pendant against such movement.

24. In a watch, the combination with a movement-ring, and an endwise-shiftable winding and setting stem, of a pendant movable with respect to the movement-ring and operatively connected with the winding and setting stem to shift the latter, and a locking device engaging the pendant to normally prevent such movement of the latter as would serve to shift the stem.

25. In a watch, the combination with a movement-ring and case, of a pendant having threaded connection with one of said elements, an endwise-shiftable winding and setting stem operatively related to the pendant, and arranged to be shifted by the movement of the pendant, and means for normally locking said pendant to prevent the accidental unscrewing thereof.

26. In a watch, the combination with the

case and movement-ring, of a pendant having threaded connection with the movement-ring and engaged by the case to prevent accidental unscrewing of the pendant, and an endwise-shiftable winding and setting stem operatively related to the pendant to be shifted by the movement of the latter relative to the movement-ring.

27. In a watch, the combination with the movement-ring and case, of a shiftable winding and setting stem, a pendant having threaded connection with the movement-ring and interlocking engagement with the case, said pendant being operatively connected to the winding and setting stem to shift the latter.

In testimony that I claim the foregoing as my own I have hereto affixed my signature in the presence of two witnesses.

JOHN ZELLY.
